AUTOMOBILE FLOOR MAT

Joseph C. Breneman, Wooster, Ohio, assignor to The Wooster Rubber Company, Wooster, Ohio

Application February 27, 1956, Serial No. 40,379

Term of patent 14 years

(Cl. D9—6)

The opposite side of the mat from that shown in Figure 1 is flat and unornamented, as indicated by the sectional views.

I claim:

The ornamental design for an automobile floor mat, substantially as shown and described.
